US0D1004721S

(12) **United States Design Patent** (10) **Patent No.:** **US D1,004,721 S**
(45) **Date of Patent:** **** Nov. 14, 2023**

(54) **MODULAR BASE PANEL**

(71) Applicant: **Recreational Systems International B.V.**, Valkenswaard (NL)

(72) Inventors: **Arnoud Fiolet**, Valkenswaard (NL); **Hans Borgers**, De Pinte (BE)

(73) Assignee: **RECREATIONAL SYSTEMS INTERNATIONAL B.V.**, Valkenswaard (NL)

(**) Term: **15 Years**

(21) Appl. No.: **29/887,869**

(22) Filed: **Mar. 24, 2023**

Related U.S. Application Data

(63) Continuation of application No. 35/512,955, filed on May 14, 2021 (U.S. filing date under 35 U.S.C. 384), and having an international filing date of May 14, 2021, now Pat. No. Des. 984,566.

(57) **CLAIM**

The ornamental design for a modular base panel, as shown and described.

DESCRIPTION

FIG. 1 is a top perspective view of a modular base panel showing our new design;

FIG. 2 is an enlarged view of the portion 2 encircled in FIG. 1;

FIG. 3 is a top plan view thereof;

FIG. 4 is a front view thereof;

FIG. 5 is a back view thereof;

FIG. 6 is a right view thereof; and,

FIG. 7 is a left view thereof.

The dashed broken lines in the figures illustrate portions of the modular base panel that form no part of the claimed design. The dot-dashed broken lines in the figures encircling a portion of the claimed design that is illustrated in an enlarged view form no part of the claimed design.

1 Claim, 5 Drawing Sheets
